[57] CLAIM

The ornamental design for a combined toy typewriter and loudspeaker therefor, substantially as shown and described.

DESCRIPTION

FIG. 1 is a perspective view of a combined toy typewriter and loudspeaker therefor, showing my new design;

FIG. 2 is a left side perspective view thereof;

FIG. 3 is a right side perspective view thereof; and

FIG. 4 is a rear perspective view thereof.

The bottom of the combined toy typewriter and loudspeaker therefor is plain and unornamented.

FIG. 1

FIG. 2

FIG. 3

FIG. 4
